RUBBER SOLE FOR SPORT SHOES

Fritz Kappeler, Bulach, Switzerland, assignor to
 Aktiengesellschaft R. & E. Huber, Schweizerische Kabel-, Draht- und Gummiwerke, Pfaffikon, Switzerland

Application May 2, 1944, Serial No. 533,699
 In Switzerland January 27, 1943

2 Claims. (Cl. 36—59)

The present invention relates to rubber soles for sports shoes, particularly for ski or mountain shoes, having its tread surface provided with projections to prevent slipping. The object of the invention is to provide a rubber sole for sports shoes having improved non-slip features.

According to the invention, a greater security against slipping is obtained in that the projections extend along a broken line and are of such shape that no through-passing straight interstices extending to the edge of the sole, which would favour slipping, are present in any direction in the plane of the sole between the projections, while the interstices provided between the projections of the sole and of the heel form re-entering angles the points of which are forwardly directed at the sole and rearwardly at the heel, in order to create opposed wedging effects on the sole and on the heel to increase the security against slipping.

The accompanying drawing represents by way of example a preferred embodiment of the invention.

Fig. 1 is a view on the tread surface of a rubber sole according to the invention.

Fig. 2 is a longitudinal section along the broken line II—II of Fig. 1.

Fig. 3 is a partial view of the tread surface of the sole drawn to a greater scale.

Fig. 4 is a transverse section along the line IV—IV of Fig. 3.

The represented sole 1 is provided along its lateral marginal portions with projections 2 extending in zigzag shape and which are alternatively separated by larger interstices 6 and narrower interstices 6' so as to form pairs. In the central portion of the sole there are provided further projections 3 also extending along a broken line and having different shapes. These projections 3 are so disposed that they intercept the extensions of the passages formed by the interstices 6 and 6' between the marginal projections 2. The front end of the sole is provided with projections 4 which are larger than the projections 2, and the interstices 5 between these projections 4 are of smaller depth than the interstices 6 and 6' between the projections 2. In this manner a reinforcement of the sole is obtained at the point thereof which is subjected to increased wear.

The heel 7 is provided with projections 8 along its lateral marginal portions which are disposed in pairs similar to the projections 2 of the sole, and are also extending along a broken, zigzag-shaped line. An angular-shaped projection 9 is

formed in the central portion of the heel 7, while the rear end of the heel is provided with projections 10 which are larger than the projections 8, and the interstices 11 between these latter projections also are of smaller depth than the interstices 12, 12' between the projections 8, so as to obtain a reinforcement at the rear end of the heel also subjected to increased wear.

It is apparent from the drawing, that the projections 2, 3 and 4 of the sole, and the projections 8, 9 and 10 of the heel 7 are of such shape and so disposed, that no through-passing straight interstices extending to the edge of the sole, which would favour slipping are present in any direction in the plane of the sole. Moreover, the projections 2 and 8 of the sole 1 and of the heel 7 are formed with interstices having re-entering angles 6'' and 12'' the points of which are forwardly directed at the sole and rearwardly at the heel, in order to produce opposed wedging effects on the sole and on the heel to increase the security against slipping. Owing to this arrangement, when mounting with shoes equipped with the represented sole, the non-slip features 25 of the sole are particularly effective, while when descending the non-slip features of the heel are effective.

As can be seen from Figs. 3 and 4, the lateral limiting surfaces of the narrower interstices 6' between the projections 2 of a pair of projections have a greater conicity than the lateral limiting surfaces of the larger interstices between the pair of projections 2, the distances *a* in Fig. 4 being greater than the distances *b*. Also at the heel 35 the lateral limiting surfaces of the interstices 12' between the projections 8 have a greater conicity than the lateral limiting surfaces of the larger interstices 12 between the pairs of projections 8. This arrangement facilitates expelling 40 of small articles clamped between the projections when walking, such as small stones.

The portion of the sole between the projections 2 and the heel can be provided with the manufacturer's trade-mark, which may consist of 45 relieved letters formed in the material of the sole, so as to obtain a security against sliding also at this portion of the sole.

I claim:

1. A rubber sole for sports shoes having a tread surface provided with zigzag-shaped projections along the lateral marginal portions of the sole, a heel surface also provided with zigzag-shaped projections along the lateral marginal portions thereof, said projections on the sole and on the heel being separated by interstices forming re-

entering angles having the points thereof forwardly directed at the sole and rearwardly directed at the heel, the front end of the sole and the rear end of the heel being provided with projections of larger area than that of said projections formed on the lateral marginal portions of the sole and the heel, the projections on the front end of the sole and on the rear end of the heel being separated by interstices of smaller depth than that of the interstices formed between the projections provided between the lateral marginal portions of the sole and the heel.

2. A rubber sole for sports shoes having a tread surface provided with zigzag-shaped projections along the lateral marginal portions of the sole, and a heel surface also provided with zigzag-

shaped projections along the lateral marginal portions thereof, said projections on the sole and on the heel being arranged in pairs separated by interstices, and the projections of one pair being separated by narrower interstices than those separating the pairs of projections, said interstices having inclined lateral limiting surfaces and forming re-entering angles having the points thereof forwardly directed at the sole and rearwardly directed at the heel, the lateral limiting surfaces of the narrower interstices between two projections of one pair having a greater concavity than the lateral limiting surfaces of the larger interstices between the pairs of projections.
